LEO ROSENMAN, OF NEWARK, NEW JERSEY.

FASTENING FOR WOMEN'S UNDERGARMENTS.

Application filed February 18, 1925. Serial No. 10,016.

This invention relates, generally, to improvements in women's undergarments; and the invention has reference, more particularly, to an improved arrangement and construction of fastenings for women's undergarments, such as brassières, underwaists, and similar garments.

The invention has for its principal object to provide a garment with a novel arrangement and construction of fastening means for uniting the meeting edges of the garment to furnish a gapeless closure of the kind known in the art as a "French closing", while at the same time providing an arrangement of fastening means which permits the wearer to selectively fasten the garment in either comparatively loose fitting or in tight fitting relation to the body, as may be desired; such an arrangement permitting the wearer to adjust the garment loosely for comfort, but snugly or tight fitting for dress occasions or for reducing purposes. To the above ends the novel fastening arrangement and construction for the garment consists of hook and eye fasteners in the form of hook tape and eye tape, which are respectively secured to the respective meeting edge portions of the garment. The eye tape is constructed to provide two substantially vertical rows of eyes, one row (viz the inner row) being disposed in rearwardly spaced relation to the other (viz, the outer row), and the front of the garment being united or secured to the eye tape in such novel manner, that the loops of the outer row of eyes will project laterally from one meeting edge of the garment toward the opposite meeting edge thereof to which the hook tape is secured, while the loops of the inner row of eyes are caused to project outwardly through perforations in face of the garment so as to be exteriorly exposed for engagement by the hooks of the opposite garment-edge, but spaced a desired distance to the rear of said projecting loops of the outer row of eyes. The distance separating the outer and inner rows of eyes will constitute the amount of "take-up" provided in the garment fastening, as between a comparatively loose fitting and a desired tight fitting of the same. The novel arrangement of eye loops relative to the face of the garment is such, that a neat appearance of the garment is retained, even when the garment

is loosely worn, while when worn in tight fitting condition all eye loops are concealed.

Other objects of this invention, not at this time more particularly enumerated, will be clearly understood from the following detailed description of the same.

The invention is clearly illustrated in the accompanying drawings, in which:—

Figure 1 is a front view of a brassière furnished with the novel arrangement and construction of fastening means made according to and embodying the principles of this invention; Figure 2 is an enlarged fragmentary view of portions of the meeting edges of the garment as closed by the novel arrangement and construction of fastening means for comparatively easy or loose fitting relation to the wearer's person; Figure 3 is a similar view as closed by the novel arrangement and construction of fastening means for tight-fitting relation to the wearer's person; Figure 4 is an enlarged fragmentary face view of the meeting edge of the garment equipped with the novel arrangement of eye fasteners, a portion of the garment body being broken away to show a face view of the tape body by which the eye fasteners are supported; and Figure 5 is a transverse section, on a further enlarged scale, taken on line 5—5 in Figure 4.

Figure 6 is a fragmentary face view of a modified construction of eye tape attached to the body of a garment; and Figure 7 is a transverse section, on an enlarged scale, taken on line 7—7 in Figure 6.

Figure 8 is an enlarged fragmentary face view of the meeting edge of the garment equipped with a modified form of the novel arrangement of eye fasteners, a portion of the garment body being also broken away in this view to show a face view of the tape body by which the eye fasteners are supported; and Figure 9 is a transverse section, taken on line 9—9 in said Figure 8.

Similar characters of reference are employed in all of the hereinabove described views, to indicate corresponding parts.

Referring now to Figures 1 to 5 inclusive, the reference character 10 indicates a women's undergarment, such, for example, as a brassière. Secured by stitching to the inner face marginal portions of one meeting edge 11 of the garment opening is a hook-tape 12 to which are firmly secured fastener

hooks in desired longitudinal spaced apart relation, and so that the bills 13 of the fastener hooks are properly exteriorly projected along the inner face of said meeting edge 11 of the garment.

The reference character 14 indicates the base strip of an eye-tape. Secured upon said base strip 14 in longitudinally spaced apart relation, at distances corresponding to the spacing of the bills 13 of the hooks of the hook-tape 12, are a plurality of eye fasteners 15 constituting an outer row thereof, the loops 16 of which project toward an adjacent longitudinal edge of said base strip 14. The bodies of said eye fasteners 15 are covered by a cover strip 17, said cover strip being secured by longitudinal rows of stitches 18 in such manner that the eye fasteners are strongly attached to said base strip 14, and firmly held against displacement therefrom. The loops 16 project exteriorly beyond the cover strip 17 so as to be exposed for engagement by hook fasteners. Secured upon said base strip 14, in corresponding longitudinally spaced apart relation, and also spaced behind said eye-fasteners 15 a desired distance, are a plurality of eye-fasteners 19 constituting an inner row thereof, the loops 20 of which project toward the outer row of eye fasteners 15. The bodies of said eye fasteners 19 are covered by a second cover strip 21, the same being secured by longitudinal rows of stitches 22 in such manner that the eye fasteners 19 are strongly attached to said base strip 14, and firmly held against displacement therefrom. The loops 20 freely project exteriorly beyond the cover strip 21.

In applying the eye-tape, constructed as above described, to the garment 10, the opposite meeting edge portion 23 of the garment opening is laid, outer face downward, upon the upper face of the eye-tape, with its raw edge 24 directed toward the rearward longitudinal edge of said eye-tape. Said meeting edge portion 23 is thereupon secured by stitching 25 to the base strip 14 of the eye-tape, said stitching 25 preferably traversing the bases of the loops 16 of the outer row of eye-fasteners 15 close to the adjacent outer edge of the cover strip 17, or, if desired, the stitching 25 may be run back of the eye fasteners 15, leaving the marginal edge portion free so as to form a fly. The garment is now turned along the line of stitching 25 face outward so as to extend rearwardly over the upper face of the eye-tape, thus leaving the loops 16 of the outer row of eye-fasteners 15 exposed beyond the margin 23' of the meeting edge portion 23 of the garment opening, so that said loops 16 are exteriorly projected subject to operative engagement by the bills 13 of the hook-tape 12 which is secured to the meeting edge 11 of the garment, when closing the latter

in loosely fitting relation to the person of the wearer. The garment having been thus turned back over the eye-tape, the body of the garment is secured to the rearward or inner longitudinal marginal portion of the base strip 14 of the eye-tape by a second line of stitching 26. The face of the garment to the rear of the margin 23' of its meeting edge portion 23, where the same extends over the second row of eye fasteners 19, is provided with a substantially longitudinal row of perforations, slits or incisions 27, preferably corresponding in spacing to the spacing of said second row of eye fasteners 19. The free ends of the loops 20 of said second row of eye fasteners 19 are projected through said perforations, slits or incisions 27, so that the same are exteriorly exposed at the outer face of the garment, subject to operative engagement by the bills 13 of the hook-tape 12 secured to the meeting edge 11 of the garment, when closing the latter in tight fitting relation to the person of the wearer.

Referring now to Figures 6 and 7 of the drawings, I have shown therein a somewhat modified arrangement of the eye-fastener portion of the garment. In this construction, I employ an eye-tape consisting of the base-strip 14, with the outer row of eye-fasteners 15 with free loop portions 16, said eye fasteners being secured to said base strip 14 and covered with the cover strip 17, and an inner row of eye fasteners 19 with free loop portions 20, said eye-fasteners 19 being secured to said base strip 14 and covered by said cover strip 21, all in the manner above described, and as indicated by similar reference characters applied to said Figures 6 and 7. Instead, however, of securing the body of the garment 10 in covering or overlaid relation to such eye-tape, I provide the latter with an outer facing strip 28, preferably matching in kind and appearance the material out of which the face of the garment 10 is made. The outer marginal edge 29 of said facing strip 28 is secured by stitching 30 to the base strip 14, said stitching 30 traversing the bases of the loops 16 of said outer row of eye fasteners close to the adjacent outer edge of the cover strip 17, or, if desired, the stitching 25 may be run back of the eye-fasteners 15, leaving the outer marginal edge portion of the facing strip free, so as to form a fly, thus leaving said loops 16 exteriorly projected subject to operative engagement by the bills 13 of hook tape 12. Said outer facing strip 28 extends rearwardly over the second row of eye fasteners 19 and the cover strip 21 thereof, so that the rearward longitudinal edge 31 of said facing strip is aligned with and above the rearward longitudinal edge of said base strip 14. Initially said rearward longitudinal edge 31 of said facing strip 28

is unsecured to said base strip 14, so that when applying the eye-tape faced therewith to the meeting edge portion 23 of the garment opening, said meeting edge portion 23 5 may be inserted between the rearward marginal edge portion of said base strip 14 and the rearward marginal edge portion of said facing strip 28, and all said parts thereupon secured together by stitching 32. Said facing strip 28, where the same extends over the second row of eye fasteners 19, is provided with a substantially longitudinal row 10 of perforations, slits or incisions 33, preferably corresponding in spacing to the spacing of said second row of eye fasteners 19. The free ends of the loops 20 of said second row of eye fasteners 19 are projected through said perforations, slits or incisions 33, so that the same are exteriorly exposed 15 at the outer face or side of said facing strip 28 subject to operative engagement by the bills 13 of the hook tape 12 at the opposite side of the garment opening.

Referring now to Figures 8 and 9 of the drawings, I have shown therein a further modified arrangement of the eye-fastener portion of the garment. In this latter form or embodiment of my invention I employ an eye-tape comprising a tape body or web 34. Secured to this body or web 34, adjacent to its outer longitudinal edge, is a row of eye-fasteners 35 attached to the body or web 34 by means of rivets 36, and so that the loops 37 of such eye-fasteners project 30 toward said outer longitudinal edge of the body or web. Also secured to said body or web 34 is a second or inner row of eye-fasteners 38, corresponding in number and spacing to those of said first row, but inwardly 35 or rearwardly off-set therefrom. Said eye-fasteners 38 are attached to the body or web 34 by means of rivets 39, and the loops 40 of said fasteners 38 project forwardly toward said first row of eye-fasteners 35.

In applying such modified form of eye-tape to the garment, I may make use of either form of attachment already above described, but prefer to secure the meeting edge portion 23 of the garment 10 by stitching 25, which traverses the bases of the loops 37 of the eye-fasteners 35, so that said loops are freely projected beyond the margin 23' of said meeting edge portion, subject to operative engagement by the bills 13 of hook tape 12 at the opposite side of the garment opening. The body of the garment is then disposed to extend rearwardly over said second row of eye-fasteners 38, and is then secured 50 by a line of stitching 26 to the rearward or inner marginal edge portion of the body or web 34. The face of the garment to the rear

of said attached margin 23' is provided with said longitudinal row of perforations, slits or incisions 27, preferably corresponding in number and spacing to the number and spacing of said second row of eye fasteners 38. The free ends of the loops 40 of said second row of eye fasteners 38 are projected through said perforations, slits or incisions 27, so that the same are exteriorly exposed at the outer 70 face of the garment, subject to operative engagement by the bills 13 of hook-tape 12 at the opposite side of the garment opening.

From the above description it will be quite clear that my novel fastening means for 75 women's undergarments is adapted to provide a very convenient means for selectively closing the garment in either a comparatively loose fitting or relatively tight fitting relation to the wearer's person as may be desirable at any given time; and, furthermore, the novel fastening means produces a neat and gapeless closing of the garment opening, whether fastened in loose or tight fitting condition.

I am aware that some changes may be made in the arrangement and combinations of the various devices and parts, as well as in the details of the construction of the same, without departing from the scope of this invention as set forth in the foregoing specification, and as defined in the appended claim. Hence, I do not limit my invention to the exact arrangements and combinations of the said devices and parts as described in 90 said specification, nor do I confine myself to the exact details of the construction of said parts as illustrated in the accompanying drawings.

I claim:—

In combination with one meeting edge portion of a garment opening, eye fastener means, comprising eye-tape having outer and inner rows of longitudinally spaced eye fasteners provided with free eye loops, said meeting edge portion overlying said eye-tape and being secured thereto so that said eye loops of said outer row of eye fasteners project exteriorly from the margin of said meeting edge portion, said meeting edge portion having perforations corresponding in position to the position of said second row of eye fasteners; and said loops of said second row of eye fasteners being projected through said perforations so as to be exposed on the face of said meeting edge portion back of the margin thereof.

In testimony, that I claim the invention set forth above I have hereunto set my hand this 5th day of February, 1925.

LEO ROSENMAN.
